UNITED STATES PATENT OFFICE.

WILLIAM G. NOTT, OF TORONTO, CANADA.

TUBULAR SKATE.

SPECIFICATION forming part of Letters Patent No. 729,648, dated June 2, 1903.

Application filed August 16, 1902. Serial No. 119,838. (No model.)

To all whom it may concern:

Be it known that I, WILLIAM GORDON NOTT, of the city of Toronto, in the county of York and Province of Ontario, Canada, have invented certain new and useful Improvements in Tubular Skates, of which the following is a specification.

The object of my invention is to devise a light and strong tubular skate particularly adapted to stand the strains of hockey playing and racing; and it consists, essentially, in forming the skate-body in halves suitably shaped and brazed together on a foundation-tube to form a heel-cone, a sole-cone, and a hollow toe-strut integral with the halves of the longitudinal tube connected with the blade.

My invention further relates to the construction and arrangement of the foundation-tube and the method of connecting the sole and heel plates to the cones, substantially as hereinafter more specifically described and then definitely claimed.

Figure 1 is a plan view of the foundation-tube before it is bent into shape. Fig. 2 is a perspective view of the foundation-tube bent up into shape, showing its position relative to the blade of the skate. Fig. 3 is a perspective view of the complete skate. Fig. 4 is a perspective view of the under side of the heel-plate. Fig. 5 is a full-size cross-section of the toe-strut of the skate. Fig. 6 is a full-size vertical section through the tubular portion of the skate-body. Fig. 7 is a full-size perspective view of the upper portion of the heel-cone. Fig. 8 is a full-size vertical section through the heel-cone of the skate.

In the drawings like letters of reference indicate corresponding parts in the different figures.

In manufacturing my skate I take a piece of sheet-steel and cut it, substantially as shown in Fig. 1, to form the main tube J and two pairs of lugs a a b b and the short upwardly-extending tube c, connected to the body-tube at one end of the strip d. The edges of the metal forming the main tube are preferably left apart, so that the upper edge of the blade A may fit between them, as indicated in Fig. 2, though this construction is not essential.

The body of the skate is formed in two halves B B', each stamped out of a single

piece of metal to form flanges e f g and half each of the heel-cone D, the toe-cone E, and the hollow toe-strut F, assembled on the foundation-tube and brazed together along the upper central seam h. The flanges f g may be brazed together or secured in any other suitable manner. I prefer, however, to connect them by the plan shown in Fig. 5, in which one is bent around the other, as indicated. The blade A is secured between the flanges e by means of rivets i, passing through the flanges and through the blade.

While the heel-plate G and the toe-plate H may be secured to the heel-cone and the toe cone and strut in the ordinary manner, I prefer, for the sake of strength, to make connection in the manner now to be described. As the same plan is followed with both the heel-plate and the toe-plate, it will be understood that by describing one I also describe the other, and for the purpose of the claims the word "foot-plate" may be taken as referring to either the toe-plate or the heel-plate.

Referring particularly to the heel-plate, as shown in Fig. 4, it will be seen that integral lugs j are stamped out of it and bent downwardly, the detailed view referred to showing the plate upside down. The lugs fit within the heel-cone D and are brazed or riveted thereto. The upper end of the heel-cone preferably has a flange k formed integral with its upper edge and turned outwardly. To this flange the heel-plate may be brazed, if desired. I also deem it preferable to form lugs l integral with the cone and to pass them through openings in the heel-plate and bend them down, as indicated in Fig. 3, to make the connection between the heel-plate and the cone still more secure. These lugs are specially useful with the heel-cone, as in hockey playing there is usually a very heavy upward strain on the heel-plate. The end of the toe-plate may be connected to the upper end of the toe-strut in any desired manner—for example, by brazing or double peening.

The foundation-tube is a very important feature of my invention, as not only does it materially strengthen the skate, but is essential in the assembling of the halves of the body. It will be seen that this foundation-tube gives a surface of metal below almost every part of the seam h where the halves of the

body of the skate are brazed together. Without this support beneath this seam it would be practically impossible to strongly braze the parts together. The only parts of the 5 seam, as shown in the drawings, not underlaid by the foundation-tube are those portions near the tops of the heel and sole cones, and these parts, as seen particularly in Figs. 3 and 8, are backed by the lugs depending from the 10 sole and heel plates.

I use the word "cone" for the tubular supports of the sole and heel plates, as they are roughly conical in cross-section, as shown in Fig. 5; but I do not wish to confine myself to 15 this exact shape.

A skate constructed as I have described bears important points of advantage over those now in the market. In some of these skates the toe and heel cones are separate 20 from the longitudinal tube forming the body of the skate. In such skates there is always a weak point where the lower ends of the cones are connected with the tube. I overcome this weakness by forming these cones 25 in halves integral with the halves of the tube, so that the only joint is the central seam, where the halves of the tube are brazed together over the foundation-tube. I have avoided the weakness at the toe by means of 30 the hollow toe-strut formed in halves integral with the halves of the longitudinal tube of the skate-body. It will thus be seen that it is the formation of the body of the skate in halves, as described, which enables me to 35 make these improvements, and it is the use of the foundation-tube which enables me to assemble these halves and securely braze them together along the central seam. The halves are further tied together by the sole 40 and heel plates with their depending lugs.

I have described the lugs *a a b b*, the tube *c*, and strip *d* as being integral with the foundation-tube, and I prefer this construction, though they might, if desired, be made separate and afterward secured to the tube in a 45 suitable manner. I have also described the special method of connecting the sole and heel cones; but any well-known method might be employed for that purpose without materially 50 deducting from the value of the rest of my invention. I have stated that the body of the skate is formed in halves; but it is not essential that these halves be integral, as they might be formed of pieces brazed or otherwise 55 secured together.

A skate such as described is both exceedingly strong, light, and well adapted for hockey or, with very little alteration in shape, for racing purposes.

60 What I claim as my invention is—

1. A foundation-tube for a tubular skate formed of an integral sheet of metal bent into tubular form and cut and bent to form two pairs of upwardly-turned lugs, and a short 65 upwardly-turned section of tube at one end connected by a strip of metal with the body of the tube, substantially as described.

2. A foundation-tube for a tubular skate formed of an integral sheet of metal bent into tubular form and cut and bent to form two 70 pairs of upwardly-turned lugs, substantially as described.

3. A foundation-tube for a tubular skate formed of an integral sheet of metal bent into tubular form and cut and bent to form two 75 pairs of upwardly-turned lugs transverse to the axis of the tube, substantially as described.

4. A foundation-tube for a tubular skate formed of an integral sheet of metal bent into 80 tubular form and cut and bent to form two pairs of upwardly-turned lugs transverse to the axis of the tube, and an upwardly-turned strap at one end also transverse to the axis of the tube, substantially as described. 85

5. A foundation-tube for a tubular skate comprising the main tube, two pairs of transverse lugs extending up from the top of the main tube, and a transverse strap extending upwardly from one end of the main tube, substantially as described. 90

6. A foundation-tube for a tubular skate comprising a main tube, two pairs of transverse lugs extending up from the top of the main tube, a transverse strap extending upwardly from one end of the main tube, and a short upwardly-extending tube connected with the strap, substantially as described. 95

7. In a tubular skate a body formed in two longitudinal halves suitably secured together, 100 each half stamped out of one piece of metal and comprising one-half of a longitudinal tube and one-half each of a heel-cone, a sole-cone and a hollow toe-strut in combination with a blade secured between the lower parts 105 of the halves of the tube, a heel-plate secured to the top of the heel-cone; and a sole-plate secured to the tops of the sole-cone and the toe-strut, substantially as described.

8. In a tubular skate a foundation-tube 110 comprising a main tube; and two pairs of lugs extending up from the top of the main tube in combination with a skate-body formed in two longitudinal halves assembled on the foundation-tube and brazed together, each 115 half comprising one-half of a longitudinal tube embracing the aforesaid main tube and one-half each of a heel-cone and a sole-cone brazed to the aforesaid pairs of lugs, substantially as described. 120

9. In a tubular skate a body comprising a longitudinal tube; a heel-cone; a sole-cone; and a hollow toe-strut formed of two separate sheets of metal stamped to shape and brazed together along their central upper seam in 125 combination with a foundation-tube on which the body is assembled and which is cut and shaped to give a metal surface below the larger part of the said seam, substantially as described.

10. In a tubular skate a body comprising a longitudinal tube; a heel-cone; and a sole-cone formed of two separate sheets of metal stamped to shape and brazed together along 130

their central upper seam in combination with a foundation-tube on which the body is assembled and which is cut and shaped to give a metal surface below the larger part of the said seam, substantially as described.

11. In a tubular skate the combination of the blade A; the body formed of the two halves B, B, brazed together along the seam h, and shaped to form the longitudinal tube

J, the flanges e riveted to the blade, the flanges f and g secured together, the heel-cone D, the toe-cone E and the hollow toe-strut F; the heel-plate G secured to the heel-cone; and the toe-plate H secured to the sole-cone and the toe-strut, substantially as described.

12. In a tubular skate the combination of the blade A; the body formed of the two halves B, B' brazed together along the seam h and shaped to form the longitudinal tube J,

the flanges e riveted to the blade, the flanges f and g secured together, the heel-cone D, the toe-cone E and the hollow toe-strut F; the heel-plate G secured to the heel-cone; the toe-plate H secured to the sole-cone and the toe-strut; and the foundation-tube I cut and bent to give a metal surface below the greater part of the seam h substantially as described.

13. In a tubular skate a blade; and a body having a hollow divided cone connected therewith, in combination with a foot-plate having lugs stamped out integral therewith and bent down and brazed within the said cone over the division therein, substantially as described.

14. In a tubular skate a blade; and a body having a divided toe-cone and a divided heel-cone connected therewith, in combination with a heel-plate, and a toe-plate each hav-

ing lugs stamped out integral therewith and bent down and brazed within its appropriate cone and over the division therein, substantially as described.

15. In a tubular skate a blade; and a body having a hollow cone connected therewith having integral lugs formed at its upper edge, in combination with a foot-plate having lugs stamped out integral therewith and bent down and brazed within the said cone, and having holes formed therein through which the lugs on the cone may be passed and bent down to engage the plate, substantially as described.

16. In a tubular skate a blade; and a body having a hollow divided cone connected therewith and provided at its upper edge with an outwardly-extending flange, in combination with a foot-plate resting on the said flange and having lugs stamped out integral therewith and bent down and brazed within its appropriate cone over the division therein, substantially as described.

17. In a tubular skate a blade; and a body having a hollow cone connected therewith and provided at its upper edge with an outwardly-extending flange and integral lugs, in combination with a foot-plate resting on the said flange and having lugs stamped out integral therewith and bent down and brazed within the said cone, and holes formed therein through which the lugs on the cone may be passed and bent down to engage the plate, substantially as described.
